UNITED STATES PATENT OFFICE.

ADOLPH LIPMAN, OF CHICAGO, ILLINOIS, ASSIGNOR TO VENUS BRASSIERE CO., OF CHICAGO, ILLINOIS, A CORPORATION OF ILLINOIS.

CORSET.

Application filed April 20, 1925. Serial No. 24,609.

My invention relates to improvements in corsets, and more particularly in a corset designed to combine in one garment a girdle and a brassière.

An object of my invention is to provide a garment consisting of a girdle for controlling the figure from the waist down, and a brassière to fit and control the bust.

A further object of my invention is to provide a garment of the type described, which may be worn in comfort when sitting or walking, or with other movements or activities of the limbs.

A further object of my invention is to provide a garment of the type described, including an abdominal support which does not unduly restrict the movements of the wearer.

A further object of my invention is to provide a garment of the type described, in which bending, stooping, or reaching is permitted, due to the provision of an elastic portion which removes the strain from the shoulder straps, and also from the hose supporters.

My invention is illustrated in the accompanying drawings, forming part of this application, in which—

Figure 1 is a view of the garment in normal position on the body,

Figure 2 is a front view, a portion of the garment being opened to show the internal construction, and

Figure 3 is a detail view showing the construction of the abdominal support.

In carrying out my invention, I provide an upper brassière portion 1 made of any suitable material, and a lower girdle portion 2 which is connected at the rear by an elastic webbing 3 cut in "saw-tooth" shape and extending across the back from one side of the garment to the other, and inserted so as to stretch up and down to permit the wearer to bend forward. The girdle portion is provided with stays 4 at the rear, which extend to the bottom of the garment. At the bottom is a hem 5 which is non-elastic.

The brassière portion is provided with shoulder straps 6. The girdle portion has elongated V-shaped elastic gores 7 extending from the waist to the bottom of the garment on either side thereof. At the bottom are the hose supporters 8.

On the inside of the garment is secured

on one side thereof (see Figure 3) a strip of elastic webbing 9 which is provided with two reenforcing strips 10, each of these reenforcing strips having a row of eyes 11. On the opposite side of the center is a similar strip of elastic webbing 12, which is secured to the garment 2. Secured to the elastic 12 is an abdominal supporting member. This is a "full floating" cloth support 13 which is boned with light weight steels 14. It will be noted that there is a central steel, with other steels arranged in a pyramidal form so as to radiate the control from the point at the center of the diaphragm down over the abdomen. On the edge of the abdominal support are hooks which are arranged to engage either of the rows 11. It will be observed that this abdominal support is substantially below the waist-line so as to form an efficient supporting member while permitting the body to bend above it.

The combined girdle and brassière is fastened on the left front side, hooks and eyes being provided for the purpose as shown at 15 and 16 respectively.

From the foregoing description of the various parts of the device, the operation thereof may be readily understood. In adjusting the garment, the abdominal support is first fastened, and then the hooks 15 are hooked into the eyes 16, so as to close the garment. The adjustment of the abdominal support is automatically obtained by the elastic sections on each side thereof, and additional adjustment may be had by the use of two rows of eyes. This support holds the internal organs in place, where they belong, but without undue restriction.

At the back, the elastic connection between the upper or brassière portion and the lower or girdle portion permits the garment to stretch, as in bending, stooping, or reaching, and it also removes the pull from the shoulder straps. The boning at the back from the waist down is scientifically placed so as to make the garment "cut-in" around and just below the fleshy part of the back, thus affording comfort and shapeliness to the figure.

I claim:

An undergarment comprising a brassière portion, a girdle portion, an intermediate elastic portion secured to said girdle por-

tion and said brassière portion and extending across the back from one side of the garment to the other, an abdominal supporting member, an elastic webbing secured to each side of said abdominal supporting member and to the interior of the garment, said abdominal supporting member having a

central stiffening strip terminating below the waist line, and auxiliary strips secured to said central strip and being inclined 10 downwardly and outwardly with respect to the central strip.

ADOLPH LIPMAN.
